[57] CLAIM

The ornamental design for a seal lock body, as shown and described.

DESCRIPTION

FIG. 1 is a perspective view of a seal lock body showing our new design, the broken-line showing of the shackle and cabinet hardware being for illustrative purposes only and forming no part of the claimed design; FIG. 2 is a front elevational view thereof, the rear being a mirror image;

FIG. 3 is a top plan view thereof;

FIG. 4 is a bottom view thereof;

FIG. 5 is a right side elevational view thereof;

FIG. 6 is a left side elevational view thereof;

FIG. 7 is a vertical cross-sectional view thereof, taken alone line 7—7 of FIG. 3;

FIG. 8 is a vertical cross-sectional view thereof, taken along line 8—8 of FIG. 4;

FIG. 9 is a front elevational view of an alternate embodiment thereof, the rear being identical in appearance;

FIG. 10 is a top plan view of the embodiment of FIG. 9;

FIG. 11 is a bottom plan view thereof; and,

FIG. 12 is a left side elevational view thereof, the right side being identical in appearance.
